UNITED STATES PATENT OFFICE.

CHARLES BALOUGH OF SPRINGFIELD, OHIO.

INTERNAL-COMBUSTION ENGINE.

1,195,550.

Specification of Letters Patent. Patented Aug. 22, 1916.

Application filed April 22, 1914. Serial No. 833,633.

To all whom it may concern:

Be it known that I, CHARLES BALOUGH, a subject of the Emperor of Austria-Hungary, residing at Springfield, in the county of Clark and State of Ohio, have invented certain new and useful Improvements in Internal-Combustion Engines, of which the following is a specification.

This invention relates to improvements 10 in internal combustion engines and more particularly relates to the valves and their operating mechanism.

An object of the invention is to provide a valve for the intake and exhaust ports and 15 devices for operating the same which will be simple and effective in operation and also in which the noise due to the operation is reduced to the minimum.

A further object of the invention is to de- 20 vice a construction in which the operating shaft or shafts for the valve may be run at substantially engine speed, thus enabling me to utilize the shaft for operating such accessories as the magneto, electric starter, generator, tire pump, etc., without the necessity of intermediate speed changing gearing by coupling these accessories directly to said shaft.

A further object of the invention is to de- 25 vice a construction in which the gears incorporated in the operating devices for the valves may be alike as to size, as a result of which a decided manufacturing advantage is obtained.

A further object of the invention is to 30 provide a construction in which the timing of the valves can be readily and easily accomplished without the necessity of making any changes in the relation between the operating gears.

A further object of the invention is to 35 provide a construction whereby the proper timing of the valves will enable the engine to be reversed without the necessity of making any changes in the operating devices.

A further object of the invention is to 40 provide a construction whereby the valves may be driven at any speed, or at different speeds with respect to each other, if at any time found desirable, by simply changing the ratio between the gears on the operating and driven shafts.

A further object of the invention is to de- 45 vice a construction which will permit of intake and exhaust ports of ample size and in which also a compression chamber may be

provided of the most effective shape and so designed as to be capable of being machine finished to secure uniformity in the compression chamber.

A further object is to provide a valve which will be self-adjusting for the purpose of taking up the wear.

A further object is to so arrange the valve in its relation to the cylinder that it could be operated in a simple and noiseless manner.

In the accompanying drawings:—Figure 1 is a top plan view of an internal combustion engine embodying my improvements. Fig. 2 is a diagrammatic view of the cylinders and valves showing the relative positions of the same with respect to each other. Fig. 3 is a longitudinal section on the line 3—3 of Fig. 1. Fig. 4 is a vertical section on the line 4—4 of Fig. 3. Fig. 5 is a vertical section of a portion of one of the cylinders and one of its valves, showing the upper portion of the valve stem. Fig. 6 is a vertical section of the lower portion 70 of the valve stem and its operating devices. 75

Like parts are represented by similar characters of references in the several views.

The engine which I have illustrated in the drawings is one of the 4-cycle type employing four cylinders, the cylinders being indicated by 1, 2, 3, and 4. The water jacket for these cylinders is indicated by 5; 6 is the crank casing; 7 the crank shaft; 8 the cranks and 9 the piston-rods. In the present case I have shown two removable water jacketed heads 10 and 11, which not only form the heads for the cylinders but also contain bearings for the valves to be hereinafter described; each head being associated with two cylinders.

Journalized in suitable bearings in the crank casing 6 parallel with the crank shaft are two shafts 12 and 13, arranged to be driven at engine speed from the crank shaft either by a chain or gears. In the present case the crank shaft is provided with a sprocket-wheel 14 and each of the shafts 12 and 13 has a sprocket 15 over which sprockets pass a chain 16, although if desired gears can be substituted for these sprockets and chain.

Located in the heads 10 and 11 are four valves, 17, 17', 18, and 18'; 17 and 17' representing the exhaust valves and 18, 18' the intake valve. Each head carries one exhaust and one intake valve arranged on op-

posite sides of the head and common to both of the cylinders corresponding to that head, the relation of the valves and cylinders being illustrated in Figs. 1 and 2.

- 5 Each of the valves is formed of a cone shape and the bearing or seat for the valves is of a similar shape. Each valve is provided with an intake or exhaust port 19, as the case may be, adapted to communicate
- 10 with the inlet or outlet port 20 in the head of the cylinder, which port communicates with the combustion chamber 21 in the usual way. The upper end of each valve is open so as to communicate with the manifold
- 15 pipes 22; these manifold pipes being held in position on the respective heads by cross-bars 23 arranged to be clamped against the pipes by bolts 24 secured to and projecting upwardly from the respective heads through
- 20 the bars and provided with nuts on the outer screw-threaded ends thereof so that the bars may be firmly clamped against the pipes.

The respective valves are driven from the 25 shafts 12 and 13. Each valve has connected therewith a downwardly projecting stem 25, the lower end of which has a tongue and groove connection with the short upwardly extending shaft 26, this shaft 26 having connected therewith a worm gear 27 in mesh with a worm 28 upon the shaft 12 or 13 as the case may be; the relation of these worms and worm gears being such that the valves will be rotated at the proper speed.

- 30 In order that the valves may be properly timed without the necessity of changing the relation of any of the shafts or gears with respect to each other, the upper end of the shaft 26 is provided with an adjustable 35 collar 29 arranged to be held in different positions of adjustment by the set screw 30. This collar has a tongue 31 adapted to project in a groove in the head or collar 32 on the lower end of the valve stem 25; this 40 collar 32 being in the present case shown as a separate piece secured to the stem by a screw 33, although if desired it may be integrally formed with said stem. After the parts have been assembled and before the
- 45 manifold pipes have been placed in position, it will be seen that by unloosening the set-screws 30 the valves may be turned to the proper position for the correct timing thereof, after which the set screws will be 50 tightened to firmly connect the collar 29 with its shaft, thus providing a very simple, easy and accurate manner of timing the valves. Access is obtained to the set screw 30 by raising the cover 34 which will slide 55 upwardly within the casing 35 against the tension of a spring 36 interposed between the upper end of the casing 35 and the plug or head 38 connected with the upper end of the cover 34, the spring tending to normally 60 hold the cover 34 against a seat formed on

the upper side of the bearing 39 for the shaft 26, which bearing is located in the crank case 6.

Means are provided for making the valves self-adjusting in their seats to take up wear, 70 this being accomplished in the manner illustrated in detail in Fig. 6. Extending upwardly through the shaft 26 is a rod 40, the upper end of which projects into a chambered part of the shaft 26 and is connected 75 with a spring 41 therein, the other end of the spring being connected with a pin 42 which has a screw-threaded connection with the valve stem 25. The lower screw-threaded end of the rod 40 is provided with adjusting 80 nuts 43 for the purpose of adjusting the tension of the spring so as to apply a gentle downward pressure upon the valve stem and its valve.

By the constructions described, there are 85 provided valves and operating devices therefor which will operate more quietly than the puppet valve type; further, by having the valve operating shafts 12 and 13 driven from the crank shaft at engine speed, or substantially so, I am enabled to directly connect with these shafts such accessories as the magneto, electric starter, generator, tire pump, etc., thus eliminating all intermediate gearing. It will further be seen that all of 90 the sprocket wheels, or driving gears, if gears be employed, may be of a uniform size and that this is also true of the worm gears and worms 27 and 28, resulting in a decided manufacturing advantage. It will further 95 be seen that the manner of timing the valves is such that the valves may be timed in a quick and easy manner without disturbing any of the operating shafts and gearing; this construction also permitting a more 100 accurate adjustment of the valves than can be had by resetting the time gears and cams found necessary in other types of internal combustion engines. Another advantage due to this construction is that by properly 105 timing the valves, the engine may be run in the reverse direction without the necessity of changing the valve operating devices; also, if at any time found desirable, the valves may be driven at any speed, or at 110 different speeds with respect to each other, by varying the relation of the gearing. It will also be seen that by arranging the valve so that its axis will be parallel with the axis of the cylinder, the manner of driving the 115 valve may be simplified and that the cone-shape of the valve and seat permits the valve to self-adjust itself to take up wear.

Having thus described my invention, I 120 claim:

1. The combination of a cylinder, a rotatable cone-shaped valve together with means for operating the same, a similarly shaped seat for said valve, a valve stem connected with said valve, a shaft in line with 125

said valve stem and operatively connected therewith together with means for operating said shaft, a spring in said shaft connected with said stem, and means carried by said shaft for adjusting the tension of said spring.

2. The combination of a cylinder, a rotatable valve, a valve stem connected with said valve, a shaft in line with said stem together with means for operating said shaft, an adjustable member on said shaft for connecting said stem thereto, and a spring-pressed cover for said connection.

3. The combination of a cylinder, a valve and valve seat, a driven shaft, and a spring-pressed connection between said driven shaft and said valve including an adjustable collar for changing the timing of said valve, substantially as described.

4. The combination of a cylinder, a valve and valve seat for same, a main driving shaft, a driven shaft connected therewith, a

tension device located within the driven shaft, means for connecting said tension device to said valve, means for adjusting the tension of said tension device, and an adjustable connection between said driven shaft and said valve for changing the timing of said valve, substantially as described.

5. The combination of a cylinder, a valve and valve seat therefor, a main operating shaft, a driven shaft operatively connected with same, a spring connecting said driven shaft with said valve, a rotatable connecting member on said driven shaft, and means connecting said rotatable member with said valve whereby the valve may be timed and same may be held yieldingly in its seat.

In testimony whereof, I have hereunto set my hand this 16th day of April, 1914.

CHARLES BALOUGH.
